UNITED STATES PATENT OFFICE.

REES BEYNON, OF CLEVELAND, OHIO, ASSIGNOR TO THE MECHANICAL RUBBER COMPANY, A CORPORATION OF NEW JERSEY.

DESIGN FOR A JAR-RING.

51,579.

Specification for Design.

Patented Dec. 18, 1917.

Application filed September 15, 1915. Serial No. 50,898. Term of patent 14 years.

To all whom it may concern:

Be it known that I, REES BEYNON, a citizen of the United States, residing at Cleveland, county of Cuyahoga, and State of Ohio, have invented a new, original, and ornamental Design for a Jar-Ring, of which the following is a specification, reference being had to the accompanying drawing, forming part thereof.

The figure is a perspective view of a jar ring, showing my new design.

I claim:

The ornamental design for a jar ring, as shown.

Signed at Cleveland, Ohio, this 3rd day of September, 1915.

REES BEYNON.

Witnesses:

EDWIN L. STIMSON,
R. T. KINSLEY.
